ATOMIZER

William A. Cotter, New York, N. Y., assignor to
Cotter Manufacturing Co., Inc., New York,
N. Y.

Application February 4, 1948, Serial No. 6,165

7 Claims. (Cl. 299—88)

1

This invention relates to atomizers. More particularly it concerns atomizers for atomizing perfume, said atomizer being adapted to be carried in the pocket or in a hand bag without danger of leakage of the liquid therein.

An object of this invention is to provide an atomizer including a casing for containing liquid, an atomizing nozzle projecting from the casing, reciprocable means for atomizing liquid from said nozzle, a member pivotally mounted on the casing which is adapted when in one position, to seal said nozzle, and is further adapted, when in another position, to form means for actuating the reciprocable atomizing means.

A further object of this invention is to provide an atomizer including a casing for containing liquid, an atomizing nozzle and an air nozzle projecting from the casing, an air pump connected to said air nozzle and including a reciprocable member having a portion thereof projecting from the casing, a member pivotally mounted on the projecting portion of the reciprocable member, said pivoted member, when in one position, sealing the atomizing and air nozzles, resilient means on said reciprocable member for maintaining the pivoted member in its sealing position, said pivoted member being adapted when moved into another position, to uncover said nozzles, and further to form a handle for actuating the reciprocable member of said air pump to cause liquid to be atomized from the atomizing nozzle, said resilient means on the reciprocable member being further adapted to maintain said pivoted member in said second mentioned position.

Another object of this invention is to provide in a device of the character described, a casing for holding liquid to be atomized, an atomizing nozzle projecting from the casing, reciprocable means on said casing for causing liquid within the casing to be atomized through the nozzle, upon reciprocation of said reciprocable means, a spring within said casing for urging said reciprocable means to a predetermined position, a member pivotally mounted on said reciprocable member, said pivoted member when in one position, sealing said atomizing nozzle, and when in another position, forming means for moving said reciprocable member from said predetermined position along a predetermined path against the biasing action of said spring, said pivoted member being formed to provide stop means for limiting the movement of said reciprocable member along said path, and to determine the maximum compression of said spring.

2

Still another object of this invention is to provide in a device of the character described, a casing for holding a liquid to be atomized, a plurality of adjacent nozzles projecting from said casing, including an atomizing nozzle, an air nozzle and a vent nozzle, reciprocable means on said casing including a portion projecting from an opening in said casing, for pumping air through the air nozzle to cause liquid to be atomized from the atomizing nozzle, a member pivotally mounted adjacent one end thereof on the projecting portion of said reciprocable member and having a resilient pad on the other end thereof, said pivoted member being normally disposed at right angles to the axis of said reciprocable member with the pad thereon sealing said nozzles, said pivoted member being adapted to be moved from said sealing position to a position in alignment with said reciprocable member, and forming a handle for reciprocating said reciprocable member when in said position, a portion of said handle being adapted to move into said casing through said opening when said reciprocable member is reciprocated.

Still a further object of this invention is to provide an atomizer including in combination, a casing formed with a liquid holding chamber, a pair of nozzles projecting from said casing and communicating with said liquid holding chamber, an air chamber within said casing, an air nozzle projecting from one end of said air chamber and disposed adjacent one of said nozzles, a pump chamber within said casing communicating with another end of said air chamber, a plunger reciprocably mounted in said pump chamber, a spring in said pump chamber for normally urging said plunger to one position, said plunger comprising a pair of ears projecting outwardly of said casing, a member pivoted at one end thereof between the ears of said plunger, said pivoted member being provided at the other end thereof with resilient material for sealing said nozzles when said pivoted member is disposed at right angles to said plunger, said pivoted member being adapted to be swung about its pivotal axis to a position in alignment with said plunger, said pivoted member being adapted when in said last mentioned position to be used as means for repeatedly moving said plunger to another position against the action of said spring, to pump air through said air chamber to said air nozzle, and a spring pressed latch on said plunger adapted to engage portions of said pivoted member to maintain said member in its first or in its second mentioned position.

Yet another object of this invention is to provide a compact perfume atomizer which is proof against leakage of the liquid contents thereof, no matter in what position the atomizer is carried, which is inexpensive to manufacture, is easy to operate, and yet is practical and efficient to a high degree in use.

Other objects of this invention will in part be obvious and in part hereinafter pointed out.

The invention accordingly consists in the features of construction, combination of elements, and arrangement of parts which will be exemplified in the construction hereinafter described, and of which the scope of invention will be indicated in the following claims.

In the accompanying drawings, in which is shown various illustrative embodiments of this invention:

Fig. 1 is a front elevational view of the device embodying the invention;

Fig. 2 is a vertical section taken on the line 2—2 of Fig. 1;

Fig. 3 is a top plan view of the device shown in Fig. 1, with parts in dotted outline;

Fig. 4 is a partial sectional view of the device shown in Fig. 2, with a pivoted member thereon in an upright position;

Fig. 5 is a vertical sectional view of the device shown in Fig. 2, with the pivoted member in a vertical, depressed position.

Fig. 6 is a sectional view taken on the line 6—6 of Fig. 2, and

Fig. 7 is a bottom view with parts in section, of the device shown in Fig. 2.

Referring now in detail to the drawing, 10 designates an atomizer embodying the invention. The same comprises a casing 11, having an upstanding front surface 12, an upstanding back surface 13 parallel thereto, a pair of curved symmetrically disposed side surfaces 14, a bottom surface 15, and a top surface 16 parallel thereto.

The casing 11 is formed with a vertically disposed cylindrical bore which constitutes a liquid holding chamber 20, extending from the bottom surface 15 towards the top surface 16, but terminating short thereof. The lower end of the chamber 20 is formed with a threaded surface 21 and an annular recess 22 of enlarged diameter. A slotted flanged head screw cap 23 is screwed into the threaded portion of chamber 20 to close the same. An annular gasket 24 may be disposed in the recess 22 in contact with the underside of the flanged head of screw cap 23, to make the closure liquid tight. The casing 11 is formed with a pair of vertically disposed passages 25, 26, extending from top surface 16 and which communicate with the interior of chamber 20.

The casing 11 is further formed with a vertically disposed narrow, cylindrical bore 30 extending from the top surface 16 towards the bottom surface 15, but terminating short thereof and forming an air chamber. The upper end of the bore 30 is formed with a portion 31 of enlarged dimensions extending to the top surface 16. The casing is further formed with a vertically disposed cylindrical bore 32 extending upwardly from the bottom surface 15 to substantially the mid-portion of the casing and constituting a pump chamber. Extending upwardly from the bore 32 and communicating therewith, is a vertically disposed passage 33 of rectangular transverse cross section. The passage 33 is of smaller dimension than the bore 32, thus forming an annular shoulder 34. The passage 33 extends to the top surface 16.

The lower end of the bore 32 is internally threaded for engaging a screw threaded closure cap 35. The cap 35 may be provided with recesses 36 on its outer surface, which are adapted to be engaged by a suitable wrench for tightening or loosening the cap. The wall separating the air chamber 30 and the bore 32 is formed with a transverse through opening 36 at the lower end thereof, to establish communication between bore 32 and air chamber 30, for the purpose hereinafter appearing.

An elongated tube 40 is mounted within the liquid holding chamber 20, with the upper portion thereof force fitted in the passage 26 and provided with a nozzle end portion 41 projecting outwardly of the top surface 16. The lower end of tube 40 extends towards the bottom surface 15, but terminates short thereof. A short air vent tube 42 is force fitted into the passage 25 and has a nozzle end portion 43 projecting outwardly of top surface 16. A right angle turret 45 has a vertical arm 46 thereof force fitted into the portion 31 of air chamber 30. The horizontal arm 47 of the turret is disposed in contact with the top surface 16 of the casing. The turret arm 46 is formed with a vertical hollow passage 48 which communicates with the air chamber 30, and from the upper end of which extends an angularly disposed passage 49 in the arm 47. A short tube 50 having an outer nozzle end 51 is force fitted into the passage 49, the nozzle end 51 being disposed adjacent the nozzle end 41 of tube 40.

Means is provided to pump air from chamber 32 to air chamber 30 through opening 36. To this end a reciprocable air pump is provided within the chamber 32. The pump comprises a piston rod or plunger 55 of transverse rectangular cross section, slidably and non-rotatably mounted in the complementary passage 33. At the lower end of piston rod 55, at the center thereof, is a projecting portion 56 on which is mounted a washer 57 normally disposed in contact with shoulder 34. Also mounted on portion 56 is a cup shaped piston 58 of synthetic rubber, rubberized fabric, leather, or the like. The piston 58 is adapted to engage the inner surfaces of pump chamber 32. A washer 59 is also threaded on the portion 56, the piston 58 being disposed between washers 57 and 59. The outer end of the portion 56 may be upset, as shown in Fig. 2, to retain the washers in place. The rod 55 comprises a pair of parallel ears 60 extending from the upper end thereof and normally projecting outwardly of the top surface 16. The ears 60 comprise outer surfaces flush with the outer surfaces of the rod 55, thereby permitting the ears 60 to move inwardly into passage 33 upon depression of rod 55. The ears 60 are formed with aligned openings 61 and rounded corners 62 on the forward upper edges thereof, for the purpose hereinafter appearing. The rod 55 is further formed with a central vertically disposed blind end bore 62a which extends to the top surface 63 of the rod. In the normal position of rod 55, the top surface 63 is disposed slightly below the top surface 16 of the casing.

Means is provided for normally urging the piston rod 55 into its rest position, with the washer 57 engaging the shoulder 34. To this end there is provided a spiral spring 65 which is mounted within the pump chamber 32, with the bottom convolution 66 thereof seated on the inner surface of closure cap 35. The top convolution 67 of the spring bears against the washer 59. It is apparent from a consideration of Fig. 2, that the

spring 65 will normally urge the piston rod 55 to its uppermost position.

Means is provided for sealing the nozzle portions 41, 43 and 51, when the atomizer is not in use. To this end there is provided a member 70 which is pivotally mounted on the ears 60 of piston rod 55. The member 70 comprises a top wall 71, a downwardly extending front wall 72, which in the normal position of the member 70, is substantially flush with the front surface 12 of the casing. The member 70 further comprises side walls 73 which include symmetrically outwardly tapering forward portions 74 extending to front wall 72. Extending rearwardly on member 70 is a solid portion 75 of reduced width, which is accommodated between ears 60 of piston rod 55. The solid portion 75 is formed with a transverse opening 76 in which is fitted a pivot pin 77, the ends of which are journaled in openings 61 in ears 60. The solid portion 75 includes a vertically disposed back surface 78, from the lower end of which there extends a forwardly and upwardly inclined bottom surface 79, for the purpose hereinafter appearing. The side walls 73 of member 70 have their outer surfaces substantially flush with the outer surfaces of the ears 60 on piston rod 55 as shown in Figs. 3 and 5.

The walls 71, 72, 73 and 74 form a hollow portion 80 on the undersurface of the member 70. A resilient pad 81 of sponge synthetic rubber or other suitable sealing material, is positioned in the forward end of the hollow portion 80, being suitably secured to the inner surfaces of walls 71, 72. When the member 70 is in its normal nozzle covering position, the pad 81 is disposed in contacting relation with the nozzle ends 41, 43 and 51, thus effectively sealing the same, when the atomizer is not in use.

Means is also provided for resiliently maintaining said member 70 in its nozzle covering position. To this end a spring pressed latch is slidably and resiliently mounted on the piston rod 55. The latch comprises a stem 85 slidably received in recess 62a in the piston rod. The latch further comprises at the upper end of the stem 85, a flanged head 86 which is disposed under the solid portion 75 of member 70, when member 70 is in its nozzle sealing position. A coil spring 87 is seated within the recess 62a, with its upper end bearing against the lower end of stem 85, thus urging the latch outwardly of the recess. It will be apparent from a consideration of Fig. 2, that the rear bottom edge 88 on the solid portion 75 of member 70, contacts the upper surface of flanged head 86 of the spring pressed latch. Since biasing action of the latch is directed against the rear edge 88 of the member 70, it will tend to urge said member in a counter-clockwise direction, looking at Fig. 2, to effectively seal the nozzle ends 41, 43 and 51.

To use the atomizer 10, the liquid chamber 20 may be conveniently filled with perfume or other liquid to be atomized by removing screw cap 23 and replacing same after filling. To atomize the liquid within the chamber 20, it is only necessary to flip the member 70 upwardly about its pivotal axis to a vertical position as shown in Fig. 4. In this position, the member 70 forms an actuating means for operating the air pump. Upon pressing downwardly on the wall 72 of the member 70, the piston rod 55 will be moved downwardly, thereby forcing air within chamber 32 to pass through passage 36, up through air chamber 30 and outwardly through nozzle 51. On releasing the member 70, the spring 65 will restore

the rod 55 to its normal upper position. On rapidly repeating the reciprocating movement of the piston rod 55, air will be blown across nozzle 41, which will cause liquid to rise in tube 40, and to be atomized therefrom, in a manner well known in the art. The vent tube 42 allows air to enter the liquid holding chamber 20, to replace the liquid removed therefrom by atomization.

When the member 70 is in its pump operating position, the latch head 86 will resiliently bear against the rear surface 78 on the member 70, to maintain said member in alignment with the rod 55. The rounded corners 62 on ears 60 permits the shouldered edges of portion 75 to pass during the pivotal movement of member 70 from its sealing position to its pump actuating position or vice versa.

It will be apparent that the member 70 will be urged into a position whereby pad 81 seals the nozzles 41, 43, 51 by means of the spring pressed latch on the rod 55, while rod 55 is retained against upward movement by shoulder 34 and washer 57. However, the member 70 is readily moved to a position in alignment with rod 55 uncovering the nozzles and ready to actuate the rod, upon applying a slight upwardly directed pressure to the front wall 72 of the member. This causes edge 88 to move across flanged head 86 of the latch, depressing the latch against the action of spring 87 until member 70 assumes a position in alignment with rod 55. After atomizing the liquid in required amounts, the member 70 is pressed downwardly by a slight pressure applied to the forward end of top wall 71 of the member. The member will then move in a counter-clockwise direction about pivot pin 77, depressing the latch until the edge 88 is disposed rearwardly of the axis of pivot pin 77, at which time, the latch will urge the member into its nozzle closing position.

The outwardly curved wall portions 74 on member 70 act as a stop for limiting the downward movement of the piston rod 55. As shown in Fig. 5, the lowermost position of the member 70 and the rod 55 attached thereto, is determined by the curved wall portions 74 which engage the upper edges of passage 33 and which prevent further movement of member 70 into passage 33. In this manner, the compressed limit of spring 65 is fixed and undue compression thereof is avoided.

It will be apparent that spring 65 is in a normally uncompressed condition when the rod 55 is at rest. The spring is only compressed when the member 70 is swung into position for reciprocating the rod 55, and is actually depressed.

If for any reason, it is desired to remove, repair, or replace spring 65 or the piston rod 55, it is only necessary to unscrew closure cap 35 to gain access to pump chamber 32.

The slot on cap closure 23 allows the use of a coin or the like to effect its removal, incident to the refilling of liquid chamber 20.

The casing 11 may be of metal or plastic and may be formed with the various chamber and bores by metal working or molding operations suitable to the material of which the casing is made.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set

forth or shown in the accompanying drawings, is to be interpreted as illustrative and not in a limiting sense.

Having thus described my invention, what I claim as new and desire to protect by Letters Patent of the United States is:

1. An atomizer, comprising a casing, having a liquid chamber, an atomizing nozzle extending from said chamber exteriorly of said casing, an air tube on said casing adjacent said nozzle, said casing being formed with a pump chamber communicating with said air tube, and a passage communicating with said pump chamber, a reciprocable member movable in said pump chamber for atomizing liquid from said nozzle, a member directly pivoted on said reciprocable member for covering said nozzle when in a horizontal position thereof, said pivoted member being swingable to a vertical position for movement into said passage and operative to directly actuate said reciprocable member.

2. An atomizer, comprising a casing formed with a liquid holding chamber, an atomizing nozzle projecting from said casing and in communication with said liquid holding chamber, means for atomizing liquid from said nozzle including a pump chamber, a plunger reciprocably mounted in said pump chamber, a member directly pivoted on said plunger, said member in a horizontal position covering said nozzle and adapted to be swung to a vertical position in alignment with said plunger for directly reciprocating said plunger, and a spring pressed slidable latch on said plunger for urging said pivoted member into its covering position while said plunger is at rest, said latch being depressed upon movement of said member to said second mentioned position.

3. An atomizer, comprising in combination, a casing having a liquid chamber, a nozzle on said casing in communication with said chamber, an air pump in said casing for atomizing liquid from said nozzle including a reciprocable and non-rotatable member for operating said pump, a member pivotally mounted on said reciprocable member for directly depressing said member when said pivoted member is in a vertical position, said pivoted member being movable to a horizontal position for covering said nozzle, said pivoted member being disposed in alignment with said reciprocable member when in said depressing position, resilient means for retaining said members in alignment, said pivoted member being disposed transversely of the axis of said reciprocable member when in said nozzle covering position, said resilient means being further adapted to retain said pivoted member in said nozzle covering position.

4. An atomizer comprising a casing including a wall, said casing being formed with a liquid holding chamber and a pump chamber, an atomizing nozzle on said casing and communicating with said liquid holding chamber, a reciprocable member in said pump chamber, resilient means in said pump chamber for moving said reciprocable member from a depressed position to an elevated position, said reciprocable member including an end portion projecting above said casing wall when said reciprocable member is in its elevated position, a member directly pivoted to the end portion of said reciprocable member for covering said atomizing nozzle while said reciprocable member is in its elevated position, resilient means between said reciprocable member and said pivoted member for biasing said pivoted member

to its nozzle closing position, said pivoted member being movable into alignment with said reciprocable member, said pivoted member in its last mentioned position forming means for directly moving said reciprocable member to said depressed position within said pump chamber wherein the end portion of said reciprocable member is disposed below said casing wall.

5. Atomizer means for a liquid holding chamber comprising a member forming a closure for said chamber, a nozzle on said member arranged for communication with the interior of said chamber, an air pump on said member for atomizing liquid from said nozzle, said pump including a reciprocable member for operating said pump, a member directly pivoted on said reciprocable member, said pivoted member being adapted to be pivoted to a vertical position to provide manually operable means for directly actuating said reciprocable member, said pivoted member including nozzle sealing means and being further adapted to be pivoted to a horizontal position for engaging said nozzle sealing means with said nozzle, and resilient means for selectively biasing said pivoted member toward said positions.

6. An atomizer comprising a casing having a chamber for holding liquid to be atomized, an atomizing nozzle projecting from said casing and communicating with said chamber, means for atomizing liquid from said nozzle including a member mounted for reciprocation on said casing and a member directly pivoted to said first mentioned member and provided with means for covering said nozzle in a horizontal position of said pivoted member, said pivoted member being movable to a vertical position and providing manually operable means for directly reciprocating said first mentioned member.

7. An atomizer comprising a casing having a chamber for holding liquid to be atomized, an atomizing nozzle on said casing and communicating with said chamber, a pump in said casing including a reciprocable member for pumping air across said nozzle, a member directly pivoted on said reciprocable member adapted when in a horizontal position to cover said nozzle, said pivoted member being further adapted when in a vertical position to provide manually operable means for directly reciprocating said reciprocable member, said pivoted member including means for limiting the extent of movement of said reciprocable member in a downward direction.
